[57] CLAIM

The ornamental design for trigger handle switch for pinball type games, as shown and described.

DESCRIPTION

FIG. 1 is a left side elevational view of a trigger handle switch for pinball type games showing our new design; the right side elevational view being a mirror image thereof;

FIG. 2 is a front elevational view thereof;

FIG. 3 is a top plan view thereof;

FIG. 4 is a bottom plan view thereof; and,

FIG. 5 is a rear elevational view thereof.

FIG. 1

FIG. 2

FIG. 3

FIG. 5

FIG. 4
